(57) **CLAIM**

The ornamental design of the battery cover as shown and described.

DESCRIPTION

FIG. 1 is a top perspective view of a battery cover of our new design, shown in a first state of use;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a bottom perspective view thereof, shown with broken line subject matter removed to show aspects of the design that may not be visible in other views; and,

FIG. 10 is a bottom plan view thereof.

The broken lines in the drawings illustrate both environmental subject matter and portions of the article that form no part of the claimed design.
